UNITED STATES PATENT OFFICE.

WILLIAM WUTHENOW, OF CANTON, OHIO.

GAS-BURNER.

No. 918,245.

Specification of Letters Patent. Patented April 13, 1909.

Application filed July 28, 1908. Serial No. 425,738.

To all whom it may concern:

Be it known that I, WILLIAM WUTHENOW, a citizen of the United States, residing at Canton, in the county of Stark and State of Ohio, have invented a new and useful Improvement in Gas-Burners, of which the following is a specification.

The invention relates to a burner for mixing sufficient air with gas to cause complete combustion. An ordinary type of burner includes a cylindric gas drum having perforations in its forward end for the discharge of gas, and a through axial tube for the discharge of air to be mixed with the gas at the forward end of the drum; and the relative amount of air and gas in the mixture cannot be positively controlled, for the gas is freely exposed to the accession of air from all sides at the end of the drum. This primary difficulty is overcome by locating a cylindric sleeve adjacent to the forward end of the drum, by an adjustment of which sleeve the annular interval between the adjacent edges of the sleeve and the drum is adapted to be varied or closed at will, thus positively controlling the amount of outside air which can mix with the gas at the forward end of the drum. When a controlling sleeve is used, its diameter is preferably sufficiently enlarged so that the gas which is discharged from the drum and the air which is drawn through the axial tube will not entirely fill the sleeve, and the resulting suction will positively draw additional air into the mixture through the annular interval between the drum and the sleeve; the amount of additional air which is thus drawn through the drum-sleeve interval, is regulated and controlled by an adjustment of the sleeve to and from the drum, so as to make the proper mixture for causing combustion in the sleeve at the forward end of the drum. But, however nicely the controlling sleeve is adjusted, it has been found in practice that the resulting combustion, which for convenience herein is termed the initial combustion, does not completely consume all the gas, and that a certain amount of free gas is carried along with the flame through the sleeve. To overcome this supplemental difficulty, the sleeve is extended forward, by means of an adjustable tube, into a tapered ring located in and through the wall of the furnace, the forward end of the tube being approximately as large as the forward and smaller end of the ring, whereby a controllable amount of air is

drawn through the annular interval between the end of the tube and the ring, which mixes with the flame as it emerges from the tube, and serves to cause a complete combustion 60 of all the free gas which remains therein after the initial combustion.

The invention, thus described in general terms, is illustrated in the accompanying drawings, forming part hereof, in which— 65

Figure 1 is a longitudinal-vertical section of the burner in connection with the wall of the furnace; Fig. 2, a front elevation of the gas drum; Fig. 3, a front elevation of the tapered ring showing the extension tube in 70 cross section; and Fig. 4, a fragmentary side elevation of the gas drum showing a modified form of the adjusting sleeve.

Similar numerals refer to similar parts throughout the drawings. 75

The burner is composed of the cylindric drum 1, the adjusting sleeve 2, the extension tube 3 and the tapered ring 4. In the axial line of the drum is provided the air tube 5 which extends through from the rear end 80 wall to the forward end wall; and on the rear end of the drum is provided the gate 6, which by a partial or complete closure over the end of the axial tube, controls or completely stops the passage of air therethrough. 85 In the forward wall of the drum is provided the series of apertures 7 through which gas is adapted to be discharged from the drum; and the supply of gas is received through the inlet pipe 8 and is regulated by the ordinary 90 valve 9, which inlet pipe also preferably constitutes the support for the drum. The adjusting sleeve 2 is telescoped on the rear end of the extension tube 3 with reference to which it is adapted to be moved endwise, 95 preferably by means of longitudinal slots 10 in the sleeve and guide posts in the form of the screws 11 on the tube adapted to operate in the slots. The extension tube is axially supported and adapted to be adjusted endwise in the tapered ring, 4, preferably by means of the longitudinal internal ribs 12 in the ring. 100

The parts are so arranged that the sleeve and the tube can be together adjusted endwise with reference to the gas drum and the tapered ring, or they can be separately adjusted as may be desired, so as to vary or completely close the annular interval between the adjacent ends of the drum and the 110 sleeve, or the annular interval between the forward end of the tube and the tapered

walls of the ring. The adjusting sleeve may be made of larger diameter than the gas drum, in which event the rear end is provided with the inturned flange 13 which is adapted 5 to abut against the edges of the forward end of the drum to completely close the interval between the sleeve and the drum if such closure is desired, which form of construction is illustrated in Fig. 1; or, when the adjusting sleeve, as 2^a, is of equal or less diameter than the exterior diameter of the gas drum, the rear end of the sleeve is preferably provided with the flaring flange 14, as shown in Fig. 4.

15 It is evident that when gas is discharged through the apertures in the forward end of the drum, the suction caused by its current will draw a certain amount of air through the axial tube, and that by a suitable adjustment of the sleeve with reference to the drum, a sufficient additional amount of air will be drawn through the annular interval between the drum and the sleeve to cause an initial combustion in the sleeve; and that by 20 a suitable adjustment of the tube with reference to the tapered ring, the current of the initial flame will draw a sufficient amount of air through the interval between the tube and the ring to cause a combustion of all the 25 free gas which may be contained in the flame, thereby accomplishing a complete combustion, and producing the maximum heat from the same.

The extensible tube between the gas drum 30 and the tapered ring, can also be employed to control the position and character of the flame. For this purpose the drum-sleeve interval is partially or entirely closed and the air-tube gate is adjusted to prevent the mixture of enough air with the gas in the sleeve 35 to cause an initial combustion therein, and the combustion then takes place either in the forward end of the extension tube or at a point in front of the same, according to the 40 relative additional amount of air which must be drawn through the tube-ring interval to cause combustion. By greatly constricting the drum-sleeve interval and the 45 drum air-tube, and correspondingly enlarging

the tube-ring interval, a comparatively long 50 flame can be projected well forward from the end of the extension tube.

What I claim as my invention, and desire to secure by Letters Patent, is—

1. A gas burner including a drum having a 55 through tube therein and adapted to discharge gas at its forward end around the tube, an adjustable sleeve adjacent to the forward end of the drum, a tapered ring in front of the sleeve, and a second tube extending from the sleeve into the ring, whereby air drawn through the drum tube and through the drum-sleeve interval is mixed with the gas, and additional air is drawn through the tube-ring interval to cause complete combustion.

2. A gas burner including a drum having a through tube therein and adapted to discharge gas at its forward end around the tube, a sleeve adjacent to the forward end of the drum, a tapered ring in front of the sleeve, and a second tube extending from the sleeve into the ring, whereby air is mixed with the gas in the sleeve and additional air is drawn through the tube-ring interval to cause complete combustion.

3. A gas burner including a drum adapted to discharge gas and air at its forward end, a tapered ring in front of the drum, and an intervening extensible tube having its rear 80 end adjacent to the drum and its forward end terminating in the ring, whereby additional air is mixed with the gas at the rear end of the extensible tube and also at the forward end thereof, to cause complete combustion.

4. A gas burner including a drum having a through tube therein and adapted to discharge gas at its forward end around the tube, an adjustable closure for the tube, and an adjustable sleeve in front of the drum, whereby controllable amounts of air from the tube and from the rear end of the sleeve are mixed with the gas in the sleeve.
